(57) **CLAIM**

The ornamental design for a M.O.L.L.E. panel, as shown and described.

DESCRIPTION

FIG. 1 is an isometric front view of a first embodiment of a M.O.L.L.E. panel showing my new design.

FIG. 2 is a front elevation view thereof.

FIG. 3 is a rear elevation view thereof.

FIG. 4 is a partial cross-sectional view taken in the direction of line 4-4 of FIG. 2, the opposing partial cross-sectional view being a mirror image thereof.

FIG. 5 is a partial cross-sectional view taken in the direction of line 5-5 of FIG. 2.

FIG. 6 is a partial cross-sectional view taken in the direction of line 6-6 of FIG. 3.

FIG. 7 is an isometric front view of a second embodiment of a M.O.L.L.E. Panel showing my new design.

FIG. 8 is a front elevation view thereof.

FIG. 9 is a rear elevation view thereof.

FIG. 10 is a partial cross-sectional view taken in the direction of line 10-10 of FIG. 8, the opposing partial cross-sectional view being a mirror image thereof.

FIG. 11 is a partial cross-sectional view taken in the direction of line 11-11 of FIG. 8; and,

FIG. 12 is a partial cross-sectional view taken in the direction of line 12-12 of FIG. 9.

The broken lines depict portions of the M.O.L.L.E. panel that form no part of the claimed design.
